UNITED STATES PATENT OFFICE.

ANDY BOCHNAK, OF BOBTOWN, PENNSYLVANIA.

DOUBLE-ACTING RIFLE.

Application filed June 25, 1928. Serial No. 287,964.

This invention relates to a new and useful device in the nature of a double-acting rifle especially adapted for use as a weapon of warfare, game hunting, target practice and the like, embodying a means of rapidly firing a number of bullets by the operation or pulling of the trigger of the rifle.

An object of the invention is to provide a double-acting rifle of new and novel construction embodying certain adjustable features hereinafter more fully described, claimed and illustrated in the accompanying drawing.

Fig. 1 is a side elevational view of my improved rifle.

Fig. 2 is an enlarged fragmentary longitudinal central sectional view thereof.

Fig. 3 is a detail fragmentary central sectional view showing in particular the cartridge feed mechanism.

Fig. 4 is a horizontal sectional view taken on the line 4—4 of Fig. 3.

Fig. 5 is a similar sectional view taken on the line 5—5 of Fig. 3.

Fig. 6 is a front elevational view of the cartridge holder as embodied in my improved automatic rifle.

As here embodied my improved rifle comprises briefly a stock 10 of usual rifle or gun construction adapted to permit my improved rifle to be held to the shoulder of the person using same.

The main portion comprises an upper member 11 and lower member 12, attached or secured to each or by the threaded members 13, bolts, screws, studs or the like. The lower member 12 is secured to the forward extremity of the stock 10 by the threaded members 14, similar to the above described threaded members 13. The upper member 11 has formed therein an aperture adapted to receive the rear portion 15 of the rifle barrel 16 which extends therefrom and which is of the usual tubular construction, and which is rigidly secured to the said upper member 11. A grip member 17 is secured to the under upper member 11 by the clip 18, and extends therefrom directly under the barrel 16, providing a suitable grip or support for the hand of the person using my improved rifle, as is generally the practice in the use of rifles or guns.

The cartridge holder as embodied in my improved rifle comprises a band member 19 of flat ring like construction having secured thereto at its outer periphery a plurality of

tubular members 20 adapted to slidably receive the cartridges 21. The said cartridges are of the usual rifle or gun type and are provided with the usual bullets 22, which project in the usual well known manner for the forward extremity of the cartridges, and which are also provided with the usual enlarged extremities 23 or heads positioned relatively opposite the bullets 22, and which limit the engagement of the cartridges in the said cartridge holder. The band member 19 has secured thereto at its inner periphery a plurality of transverse members 24, or projections.

The cartridge holder is adapted to engage in or through an opening 25 formed in the upper and lower members 11 and 12, so as to permit the said cartridges placed therein to align with the barrel 16. The spool 26 is secured to the pin 28 rotatively mounted in the lower member 12, by means of the lock pin 29, or in any suitable manner. The spool 26 has formed therein a plurality of elongated notches 27, radially formed therein adapted to engage or receive the projections 24.

The hammer 30 is pivotally mounted on the pin 31 carried in the lower member 32, and is of the usual rifle or gun type, and has secured thereto a tension spring 32, which is also secured to the pin 33, carried in the lower member 12, as a means of normally holding the hammer 30 in a "locked" position ready for firing.

The trigger 34 is pivotally mounted intermediate on the pin 35 carried in the lower member 12 and is provided with a free extremity 36, adapted to engage the extended element 37 of the above mentioned hammer 30. The trigger 34 extends somewhat below the lower portion 12 and is protected against accidental operation, by means of the usual trigger guard 38, secured as at 39 to the lower member 12 and extended therefrom.

The firing pin 40 is slidably mounted in the opening formed intermediate the upper and lower members 11 and 12, and is normally held in a disengaged position with the enlarged head 23 of the said cartridge 21 by means of an expansion spring 41, coaxially positioned thereon, and which engages the enlarged portion 42 of the said firing pin, for the purpose as above set forth. A threaded member 43, being secured to the said upper and lower members 11 and 12, and having formed therein an axial opening through which the said firing pin 40 extends some-

what. The firing pin 40 is provided with an enlarged head 44, which is provided with a suitable extremity to accommodate or fire either center or rim fire cartridges.

5 The above described construction is such as will permit the said hammer 30, which forced forward designated by the reference numeral 45, by the pulling of the trigger 34, designated by the reference numeral 46, cause the 10 said hammer to strike the extended extremity of the firing pin 40, urging the said firing pin 40 forward and causing the enlarged extremity 44 of the said firing pin to strike the cartridge 21, exploding the cartridge and expelling or shooting the bullet 22 through the barrel 16.

A pin 47 of square transverse section is slidably mounted in the lower member 12 and is normally held in an extended position by 20 means of an expansion spring 48. The pin 47 is provided with a projection 49 adapted to engage in a notch 50 formed in the disc 51 secured to the pin 52 rotatively mounted in the lower member 12. A bevel pinion 53 is 25 secured intermediately to the pin 52 and meshes with a similar pinion 54 secured to the above mentioned pin 28, or teeth may be formed in the extremity of the said pin 28. The above described construction is such as 30 will permit the hammer 30 when operated by the trigger 34 as above set forth to strike the extended extremity of the pin 47 as a means of partially rotating the spool 26 for the purpose of partially rotating the cartridge holder 35 which will position the cartridge placed therein next to the cartridge which has been fired in alignment with the barrel 16.

Having thus described my invention what I claim as new and desire to secure by United 40 States Letters Patent is:

1. In a double-acting rifle a cartridge holder of circular band like construction having secured thereto at its outer periphery a plurality of tubular members adapted to slidably receive rifle cartridges, said cartridge 45

holder provided with inward projections adapted to engage in openings formed in a spool as a means of partially rotating the said cartridge holder when the said spool is partially rotated.

2. In combination with a double-acting rifle a cartridge holder of circular band like construction having secured thereto at its outer periphery a plurality of tubular members adapted to slidably receive rifle cartridges, said cartridge holder provided with inward projections adapted to engage in openings formed in a spool as a means of partially rotating the said cartridge holder when the said spool is partially rotated.

3. In a double-acting rifle a cartridge holder of circular band like construction having secured thereto at its outer periphery a plurality of tubular members adapted to slidably receive rifle cartridges, said cartridge holder provided with inward projections adapted to engage in openings formed in a spool as a means of partially rotating the said cartridge holder when the said spool is partially rotated, the said projections, the 60 openings in the spool, and the spool being transversely arranged.

4. In a double-acting rifle a cartridge holder of circular band like construction having secured thereto at its outer periphery a plurality of tubular members adapted to slidably receive rifle cartridges, said cartridge holder provided with inward projections adapted to engage in openings formed in a spool as a means of partially rotating the 70 said cartridge holder when the said spool is partially rotated, the said tubular members, the inward projections, the openings in the spool, and the spool being all transversely arranged relative to the said circular band 80 holder.

In testimony whereof I have affixed my signature.

ANDY BOCHNAK.
